United States Patent

Des. 237,394
Patented Oct. 28, 1975

237,394

GOLF PUTTER

William J. Priaulx, 4413 Northwestern Ave.,
Racine, Wis. 53405

Filed Apr. 8, 1974, Ser. No. 458,902

Term of patent 14 years

Int. Cl. D21—01

U.S. Cl. D34—5 GC

FIG. 1 is a perspective view of a golf putter, showing my new design.

FIG. 2 is a front elevational view thereof, with the shaft broken away.

FIG. 3 is an end elevational view thereof, with the shaft broken away.

FIG. 4 is a top plan view thereof, with the shaft broken away.

FIG. 5 is a rear elevational view thereof, taken from the side opposite from that shown in FIG. 2, and with the shaft broken away.

FIG. 6 is a sectional view taken on the line 6—6 of FIG. 5.

I claim:
The ornamental design for a golf putter, substantially as shown.
